CLAIM

The ornamental design for an electric lamp, as shown and described.

DESCRIPTION

FIG. 1 is an elevational view of an electric lamp illustrating our new design;

FIG. 2 is a top view thereof; and,

FIG. 3 is a bottom view thereof.

The base of the electric lamp, shown in phantom lines in FIGS. 1 and 3, is for the purpose of showing the environment of the lamp and forms no part of the design.
